UNITED STATES PATENT OFFICE.

GEORGE HARMS AND ROY C. WALKER, OF PEORIA, ILLINOIS.

SECTIONAL FURNACE CASING.

Application filed November 25, 1921. Serial No. 517,470.

To all whom it may concern:

Be it known that we, GEORGE HARMS and ROY C. WALKER, citizens of the United States of America, residing at Peoria, in the county of Peoria and State of Illinois, have invented certain new and useful Improvements in Sectional Furnace Casings, of which the following is a specification.

Our invention relates to furnaces, and more particularly to the so-called one-register furnaces. Our invention in particular relates to the casing which surrounds the furnace proper of a one-register furnace, said casing being formed of a plurality of sections with the result attained that ease of shipment is provided, and no particular skill required in the assembly thereof.

A further object of our invention is in the particular form of construction of the casing sections, in combination with a special means for holding said sections in a unitary structure.

Still other objects of our invention will appear in the following specification in connection with the annexed drawings, in which;

Figure 1 is a front elevation of a one-register furnace with a portion thereof shown in section.

Figure 2 is a cross-sectional view thereof.

Figure 3 is an enlarged detailed showing of the band or band members and their special form of mounting.

Figure 4 is an enlarged detail of the base ring showing the mounting of the casing sections thereon.

Figure 5 is a front elevation of one of the casing sections.

Figure 6 is a plan view thereof.

Figure 7 is a perspective of one of the sections.

Figure 8 is an enlarged detail, showing the particular form of construction of the joints between the adjoining sections.

Figure 9 is a plan view of the register.

Referring to the drawings, in which, Figure 1 is illustrative of the one-register furnace, we find the furnace proper designated generally as A. The casing generally for this furnace is designated as B, but the particular construction of this casing which forms the basis of this application will be later described. A single register is shown at C. Communication between the furnace and the single register is provided primarily by the inner conical section 10, which com-

municates with a cylindrical section 11, in connection with the register, or rather the heat portion thereof. Air surrounding the furnace, which is warmed thereby, passes through the above sections and out the register as indicated by the arrows. A second transition section 12 is connected to the outer portion of the casing B, and a squared section 13 also has engagement with the single register, with the result that cold air may return to the furnace through the conduit formed by the relative sections, taking the direction of the arrows. The forward portion of the furnace shown at D includes a plate containing the conventional projecting ash pit and combustion chamber. A base ring 14 is attached at either side of the forward portion of the furnace, said base ring surrounding the furnace proper at a determined distance therefrom. Upon this base portion or ring are stood a plurality of casing sections, the section in detail being shown in Figure 6 of the drawings.

These casing sections are made up of the following elements:

A circular inner sheet 15 forms the inner wall of the section but does not extend entirely to the bottom thereof. This inner sheet is curved in form as is the outer wall 16 of the section. The outer wall extends slightly lower than the inner wall, but only far enough to engage the base ring in the manner shown in detail in Figure 4 of the drawings. The two side walls 17 and 18 of the casing section engage the inner and outer walls in the particular manner shown in Figure 6 of the drawings. The side wall 17 has its upper portion cut away as at 19 in order that it may be engaged by the lip 20 on the side wall 18 of a related section. The side wall 17 has the flange 21 extending therefrom, formed by its engagement with the outer wall, and this flange provides an added means for positioning the plural sections. As was said before, a lip 20 is formed by an upper portion of the wall 18 being cut away and bent downwardly as at 22. A lip 23 similar to the lip 20 is formed on the lower edge of the side 17 and provides a lower attachment means for an adjacent section. A third wall 24 is shown spaced from the inner wall at a comparatively short distance, said wall conforming to the shape of said inner wall and having substantially the same relative length. This third wall has the particular engagement with the side and

inner wall as shown in Figure 6 of the drawings. Extending for some distance above the casing of the furnace is a conical section 25 having engagement with the entire inner 5 wall formed by the plural sections, whereby an extended air space is provided between the inner wall 15 of the sections and the intermediate wall 24, upon which the conical section 25 is placed. This small space 10 formed between the inner and third walls of the casing sections acts as an insulator or non-conductor of heat between the heated space about the furnace and the cool air shaft or conduit 26 in connection with the 15 register. Within the contemplation of this invention is the provision of a non-conductor chamber of the form just described which is filled with an asbestos insulator 27 shown partially in the non-conductor chamber 20 in Figure 6 of the drawings. As was stated before, the casing sections are stood upright upon the base ring 14, the side walls of each section being cut away as at 28 for engagement with the ring. In Figure 4 of 25 the drawings, a detail of the engagement of the casing section with the base ring is shown. The plurality of casing sections, due to their particular form and relative engagement portions, may be stood up around this base ring without any further connecting means therebetween, but in order to insure a more unitary structure, the band members or bands 29 are provided. In Figure 4 of the drawings a single band is all 30 that is required, in that the base ring is formed in such manner that it acts as a base for said outer band. In Figure 3 of the drawings, an inner and outer band are shown, not only acting as a means for tying 35 the plurality of sections securely together, but also, as a means for attaching the outer transition section 12 thereto. Any means may be used for attaching and drawing the bands to the forward portion or plate D of 40 the furnace. In Figure 3 of the drawings, at 30 and 31 may be seen the particular means of attaching the inner conical section 10 and section 25 respectively to the upper portion of the casing sections; it, of course, 45 being necessary to construct the upper portion of the furnace in connection with the register after the plurality of casing sections have been set up. An exit for the un-burnt fuel portions of the furnace is shown at 33. 50

55 What we claim is:

1. A hot air furnace having in combination a heater unit, a register, a casing spaced from and surrounding the heater unit to form a hot air passage, the said casing including a plurality of section units 60 detachably secured together, each section unit comprising an outer wall substantially coextensive in height with the heater unit, an inner wall spaced from the outer wall, side walls connecting the outer and inner walls together, and an intermediate wall adapted to form 65 with the outer wall an outer air passage-way, and an insulating chamber with the

and an intermediate wall coextensive in length with the inner wall and spaced therefrom to form an insulating compartment for the hot air passage, a passageway connecting the register with the passage 70 formed by the outer and intermediate walls of the casing whereby cool air is circulated downwardly through the casing, and a passageway connecting the register with the space between the inner wall of the casing 75 and the heater unit whereby the cool air is carried past the heater unit and heated thereby.

2. A hot air furnace having in combination a heater unit, a register, a casing spaced 80 from and surrounding the heater unit to provide a passage for the upward circulation of air, said casing including a plurality of separable interlocking section units, each of said section units comprising an outer wall, an inner wall spaced therefrom and an intermediate wall adapted to form a main air passage with the outer wall for the downward circulation of air, and an insulating chamber with the inner wall, 85 the said inner and intermediate walls terminating above the lower edge of the outer wall whereby communication between the downwardly circulating air passage and the upwardly circulating air passage is established, and passageways connecting said air passages to said register.

3. A hot air furnace having in combination a heater unit, a register, a casing spaced from and surrounding the heater unit to provide a passage for the upward circulation of air, said casing including a plurality of separable interlocking section unit, each of said section units comprising an outer wall, an inner wall spaced therefrom, and an intermediate wall adapted to form a main air passage with the outer wall for the downward circulation of air, and an insulating chamber with the inner wall, 100 the said inner and intermediate walls terminating above the lower edge of the outer wall, whereby communication between the downwardly circulating air passage and the upwardly circulating air passage is established, passageways connecting said air passages to said register, and means for locking 105 said casing sections together.

4. A hot air furnace having in combination, a heater unit, a register, a casing surrounding said heater unit and spaced therefrom to provide an inner air passage, the said casing comprising a plurality of separable sections, each of said sections having an outer wall substantially coextensive in 110 height with the heater unit, an inner wall spaced from the outer wall, side walls connecting the outer and inner walls together, and an intermediate wall adapted to form 115 with the outer wall an outer air passage-way, and an insulating chamber with the

inner wall, the said inner and intermediate walls being formed to provide a communication between the lower ends of the outer and inner air passages, a passageway connecting the inner air passage with the central portion of the register, and a passageway connecting the outer air passage with the edge portions of the register.

5. A hot air furnace having in combination, 10 a heater unit, a register, a casing surrounding said heater unit and spaced therefrom to provide an inner air passage, the said casing comprising a plurality of separable sections, means for interlocking adjacent sections together, each of said sections having an outer wall substantially coextensive in height with the heater unit, an inner wall spaced from the outer wall, side walls 15 connecting the outer and inner walls together, and an intermediate wall adapted to form with the outer wall an outer air passageway, and an insulating chamber with the inner wall, the said inner and intermediate walls being formed to provide 20 a communication between the lower ends of the outer and inner air passages, a passageway connecting the inner air passage with the central portion of the register, and a passageway connecting the outer air pas-

sage with the edge portions of the register. 30

6. A hot air furnace having in combination, a heater unit, a register, a casing surrounding said heater unit and spaced therefrom to provide an inner air passage, the said casing comprising a plurality of separable sections, means for interlocking adjacent sections together, each of said sections having an outer wall substantially coextensive in height with the heater unit, an inner wall spaced from the outer wall, side walls 40 connecting the outer and inner walls together, and an intermediate wall adapted to form with the outer wall an outer air passageway, and an insulating chamber with the inner wall, the said inner and 45 intermediate walls being formed to provide a communication between the lower ends of the outer and inner air passages, a passageway connecting the inner air passage with the central portion of the register, a passageway connecting the outer air passage with the edge portions of the register, and means for securing the casing in position. 50

In testimony whereof they affix their signatures.

GEORGE HARMS.
ROY C. WALKER.
